UNITED STATES PATENT OFFICE.

HUGO JUNKERS, OF AIX-LA-CHAPELLE, GERMANY.

CALORIMETER-LAMP.

No. 918,059.

Specification of Letters Patent. Patented April 13, 1909.

Application filed January 6, 1904. Serial No. 187,874.

To all whom it may concern:

Be it known that I, HUGO JUNKERS, professor in the Royal Polytechnicum at Aix-la-Chapelle, a subject of the King of Prussia, residing at Aix-la-Chapelle, No. 64 Brabantstrasse, in the Kingdom of Prussia, Empire of Germany, have invented certain new and useful Improvements in Calorimeter-Lamps; and I do hereby declare the following to be a full, clear, and exact description of the invention, such as will enable others skilled in the art to which it appertains to make and use the same.

My present invention relates to a lamp to be used for determining the heating power of liquid fuel by the aid of a calorimeter working in a state of permanency, as for instance the calorimeter described in my American Patent No. 555,956, and the object of my invention is, to produce a lamp which may be easily handled and utilized for the exact determination of the heating power without requiring any special alterations of the calorimeter and of the necessary scales.

In the accompanying drawings:—Figure 1 is a side elevation of the calorimeter lamp without a weight holding attachment, partly in section. Fig. 2 is a similar view of the lamp suspended from the beam of a pair of scales and having its burner inserted into a calorimeter. Fig. 3 is an elevation of the burner, partly in section. Fig. 4 is a plan view of the burner.

The correct determination of the heating power of a liquid fuel is only then made possible when the fuel is properly burned. To this end such a burner *a* is employed and connected in such a manner with the reservoir *b* containing the liquid fuel that the fuel led at the time being to the burner is completely burned without permitting any more difficulty burned parts of the fuel to return to the reservoir. The burner *a* shown here is a so called Swedish "Primus" burner. Its inner construction is fully shown in Fig. 3, from which may be seen that there is no room to allow a store of liquid fuel to accumulate therein, for which reason but small quantities of the liquid fuel can enter the burner and must be completely burned before new quantities can follow. For this very reason an even combustion of the fuel and a state of permanency in the calorimeter *c* is assured. Burners of a similar kind may, of course, be employed but should not contain a larger space for the liquid fuel than the illustrated burner.

The connection of the burner *a* with the reservoir *b* is made by means of a comparatively narrow and long tube *d*, which is attached at one side of the reservoir near the bottom thereof and is bent as at *e* in such a manner that the burner is standing perfectly vertical to uniformly heat the inside of the calorimeter *c* and at the same time prevent the back-flow of fuel particles into the reservoir. The vertical arm of the tube *d* is of such length as to permit of the burning lamp being pushed under the calorimeter *c* without necessitating the lengthening of the feet *f* of the calorimeter and yet be long enough to permit the flame to develop at the intended point within the calorimeter when the lamp is suspended from the beam *g* of the scales *h*. The length of the horizontal arm of the tube *d* is sufficient to prevent the lamp from contacting with the calorimeter when it is suspended from the scale beam *g*, so that the oscillations of the scales are not interfered with.

From the foregoing it will be seen, that the length of the tube *d* is dependent on the shape of the calorimeter employed. For volatile fuel it becomes necessary to hermetically close the reservoir. This would, however, result in preventing any liquid fuel from reaching the burner if the liquid fuel is not placed under a certain pressure. In order to do this, the cover *i* of the spout *k* used for refilling the reservoir *b* is provided with a relief-valve *l* of the kind used on bicycles, so that the necessary pressure in the reservoir can be obtained by means of an ordinary air pump used by cyclists.

In every instance the burner must be arranged at one side of the reservoir *b* and be connected with it by means of a narrow angularly bent tube of such a length that the burner can develop its flame at the most suitable height within the calorimeter, while the reservoir lying without the calorimeter can be suspended from the beam of a pair of scales to rise and fall without coming into contact with the calorimeter *c*. By arranging reservoir and burner side by side it is made possible to reduce the height of the lamp to such an extent that it can be passed between the feet *f* of the calorimeter without lengthening them, after which the lamp is sufficiently lifted to permit the flame to develop at the most suitable height within the calorimeter.

To be enabled to know at any moment the

pressure existing within the reservoir *b* a tube *m* is secured to the spout *k* and to its downward branch *n* a manometer *o* is fastened. The end of the tube *m* is closed by 5 means of a knurled cap *p* serving for conveniently airing the reservoir. As the burner *a* and the tube *d* are placed to one side of the reservoir *b* both would be off the perpendicular when suspended from the beam *g* of a 10 pair of scales. To avoid this, the manometer, tube *m*, spout *k* and the relief-valve *l* are placed opposite the burner *a*, thus counterbalancing the weight of the burner and tube *d*, so that burner and reservoir are occupying 15 a perfectly vertical position when suspended. To attain the greatest convenience in handling the calorimeter it is not advisable to place the lamp directly upon a pair of scales but to provide it with a hanger *q*, as in doing 20 so, on the one hand the load on the scales may be reduced or in other words the sensibility thereof be increased, and on the other hand it is made possible to remove and to replace the lamp quickly and as often as necessary 25 after the scales and the calorimeter have once been adjusted without necessitating a readjustment either of the lamp or of the calorimeter. To further simplify the handling of the lamp and to permit of the 30 scales being placed in any desirable position adjacent to the calorimeter, the rod *r* of the hanger *q* is provided with the joints *s* and *t* working at right angles to each other in order to facilitate the vertical adjustment of the

lamp, and the lower end of said rod is connected with the cover *u* of the reservoir *b* in such a manner, that on loosening the knurled nut *v* slipped over a flange *w* of the rod *r* the latter may be turned into any desirable position and held therein when the 40 nut *v* is tightened again.

If desired, a small weight-holding attachment *x* may be either permanently or removably secured to the bottom of the reservoir *b*, but its presence or absence will not in the 45 least interfere with the good working of the lamp.

I claim—

In a calorimeter lamp the combination with a closed reservoir, of a hanger for suspending said reservoir, an angularly bent fuel-conveying tube attached to the side of said reservoir, a burner carried by the free end of said fuel-conveying tube, a tubular refilling spout, means carried by the cover of 50 said spout for putting and keeping the contents of said reservoir under pressure, a venting-tube attached horizontally and laterally to said tubular refilling-spout, and a manometer suspended from said venting-tube. 55

In testimony whereof I have signed my name to this specification in the presence of two subscribing witnesses.

HUGO JUNKERS.
